UNITED STATES PATENT OFFICE.

WILLIAM F. COOPER, OF NORWALK, OHIO.

TRACKER-BAR.

1,032,467.

Specification of Letters Patent. Patented July 16, 1912.

Application filed October 27, 1908. Serial No. 459,690.

To all whom it may concern:

Be it known that I, WILLIAM F. COOPER, a citizen of the United States of America, residing at Norwalk, in the county of Huron and State of Ohio, have invented certain new and useful Improvements in Tracker-Bars, of which the following is a specification, reference being had therein to the accompanying drawing.

10 My invention relates to improvements in tracker bars, and has particular relation to the manner of connecting the bar with the tracker ducts leading to the pneumatic mechanism.

15 Self-playing musical instruments the operation of which is controlled by the use of music sheets having perforations, have generally been arranged in such manner as to provide for the use of but a portion of the 20 note-scale of the instrument. For instance, self-playing pianos have generally been provided with mechanism controlling approximately sixty-five notes of the note-scale of the piano; and the sheets prepared for a 25 note-scale of this type have their perforations arranged within the limits of this scale. It has been found, however, that this limited scale does not permit of the performance of certain classes of music, in that the 30 proper execution of the music requires a note-scale greater than that provided by the playing instrument, necessitating a change in the arrangement of the music if the selection is to be performed on the instrument.

35 To eliminate this and other objections, the note-scale has been increased to such an extent as to include substantially the entire note-scale of the piano, thereby raising the 40 number of actuating mechanisms from sixty-five to approximately eighty-eight. By this change, however, the tracker box mechanism must be lengthened to provide for the additional number of tracker ducts in the tracker bar or board, and to avoid increasing the 45 length of the board to an excessive degree, the ducts in the board have been decreased in length on the plane of the opening thereof, the general arrangement being to provide nine ducts to the inch in place of the six ducts to the inch structure used with the 50 sixty-five note-scale tracker board. Obviously, corresponding changes are made in the perforations of the music sheet, so that a music sheet formed for use in connection with a sixty-five note-scale structure and vice versa, cannot be used with the same

tracker board ducts, since the perforations in one would not coincide with the tracker duct openings used for the other. However, 55 music sheets perforated for both forms of note-scale are now in current use, and in order that either form may be employed in connection with a playing mechanism, it is necessary that the playing mechanism including the tracker box structure be formed 60 to permit of the use of music sheets of either type.

The principal object therefore of my invention is to provide a playing mechanism in which the actuating devices are equal in 65 number to the number of tracker ducts used in a note-scale of the maximum length, and in connection therewith to provide a tracker bar having tracker duct openings arranged to permit of the use of either form of music 70 sheet in connection therewith.

A further object is to provide a tracker bar having its operative duct openings located at one side of a line extending centrally along the face of the bar in a longitudinal direction.

A further object is to form a tracker bar of more than a single part, one of said parts being adjustable with respect to another part to produce a change in size of the 75 tracker ducts at the exposed end thereof.

A further object is to provide a reversible tracker bar.

A further object is to provide a tracker bar having more than a single line of tracker 80 ducts, each line having the same operative position, the positions of said lines being interchangeable to bring them into the operative position.

A further object is to provide a tracker 85 bar formed of two members, one of which is reversible end for end with respect to the other member, and means for joining the two members together when in either position.

To these and other ends the nature of which will be readily understood as the invention is hereinafter disclosed, my invention consists in the improved construction and combination of parts hereinafter fully described, illustrated in the accompanying drawings, and particularly pointed out in the appended claims.

In the drawings, in which similar reference characters indicate similar parts in each of the views,—Figure 1 is a side elevation of a tracker bar constructed in accordance

with my invention, Fig. 2 is a view looking at the opposite side of the bar, Fig. 3 is a vertical cross sectional view taken on line 3—3 of Figs. 1 and 2, Fig. 4 is a top plan view of the tracker bar, Fig. 5 is a bottom plan view of the same, Fig. 6 is a side elevation of portions of the tracker bar, showing a modified form of the means for connecting the two members of the bar, Fig. 7 is a longitudinal sectional view, partly broken away, showing the parts of the tracker bar mounted between the cheeks of a tracker box.

In view of the fact that the present invention relates solely to the construction of the tracker bar, and the fact that the manner in which the tracker ducts leading from the pneumatic action to the tracker bar and the form in which the board as a whole is mounted within the tracker box is immaterial, the disclosure herein is limited solely to the tracker bar construction, it being understood that the portion of the bar to which the permanently positioned tracker ducts are led is secured in permanent position within the tracker box, and that the ducts leading thereto are arranged in the usual manner and are of the type generally used.

The tracker board comprises two members A and B, the member A being permanently secured within the tracker box and to which the tracker ducts a lead, the member B forming what I term the reversible member. The member A is provided with openings extending vertically therethrough and arranged at one side of the longitudinal center thereof, are a series of openings a' , the number of openings corresponding to the number of ducts a . The upper face of the member A is flat, and the tracker ducts lead to the plane of the said flat face. The tracker ducts a are equal in number to the maximum note-scale, as for instance, if the music sheet comprises a scale of eighty-eight notes, the ducts a will be of equal number therewith.

The member B comprises two opposing parts b and b' , the part b having a face complementary to that of the face of the member A, while the part b' has a rounded upper face over which the music sheet passes during its movement from one spool to another. The parts b and b' are connected by tracker ducts b^2 and b^3 , these ducts being arranged in two series, each series being located on opposite sides of the longitudinal center of said parts, and having the openings of the ends of the ducts located equally distant from the side edges of the parts, viz., the openings in the part b' are in alinement in each series, and the openings of one series are spaced from the adjacent side of the part the same distance that the openings of the other series are spaced from its adjacent side, while the openings in the part b are arranged so that when the member B is reversed end for end, the openings in the part

b for one series of ducts will register with the openings in the member A, the series of duct openings of the member B equal in number to the maximum note-scale coinciding with all of the openings of the ducts in member A, while the series of the smaller note-scale register will register with a predetermined number of the duct openings in member A.

A suitable packing C, properly perforated, is interposed between the members A and B and serves to provide an air-tight joint between said members, each duct being practically continuous from one member to the other through the perforations of the packing and air-tight with respect to each other.

Any suitable means may be provided for connecting the two members A and B together. For instance, in Figs. 1, 2 and 3, I have shown the part b as having its side faces provided with a longitudinally-extending groove b^4 , one of said grooves being adapted to receive a lug d carried by a plate D secured to the member A, the opposite groove being adapted to receive the free end of a spring d' carried by the member A on the opposite side of said part, the spring d' having its end suitably shaped to normally rest within the groove. With this form of connecting means it is necessary only to withdraw the end of the spring d' from its groove and move the member B laterally to take it out of the plane of the lug d , or it is necessary only to move the member B laterally against the tension of the spring until the lug d is free from its engagement with the part b whereupon the member B may be raised and reversed, the re-positioning of the member being obtained by simply moving the spring d' and placing the part b in such position that the lug d enters its groove, the spring d' then clamping the parts together.

Another means of connecting the members together is shown in Fig. 6 in which the spring may be replaced by a plate E having one or more hooks e formed with inclined faces e' , said plate being slideable in the direction of the length of the member A, the hook or hooks e being adapted to pass over pins e^2 carried by the part b , a knob e^3 being provided to manipulate the plate. With this construction the movement of the plate in the direction of its length tends to firmly bind or to release the member B according to the direction in which the plate is moved. The construction shown in Fig. 6 may be used on one or both sides of the tracker board; where used on but one side, the opposite side may be provided with the plates D.

Owing to the fact that member B is reversible end for end, the openings for the tracker ducts contained in the part b are similar in all respects in each series of open-

ings, that is, the openings are of the same size and spaced apart the same distance in both series. This is not the case in connection with the openings at the opposite end 5 of the ducts; those openings contained in the part *b'*, in which the openings in one series are arranged to provide for the music sheet for a note-scale of eighty-eight notes, the perforations for the notes being 10 arranged on a scale of nine to the inch, while the other series is arranged for a note-scale of sixty-five notes, the notes being arranged on a scale of six to the inch. The member B may therefore be said to have its faces on 15 which the openings for the ducts are located provided with more than a single series of openings, the openings corresponding in number on both faces, the relative arrangement of the series of openings being 20 similar on the two faces.

As will be seen, the two series of tracker ducts carried by the member B are mounted to be interchangeably positioned on the single series of ducts carried by the member A, 25 and that although both series of ducts are open at the top and bottom of the member B, this fact does not affect the operation of the mechanism since but one series of ducts in the member B is in operative relation 30 with the ducts of the playing mechanism, so that the venting of the ducts of the latter mechanism can take place only in connection with the series which is in operative connection with the permanently positioned 35 ducts. And in view of the fact that the openings of the active ducts in the part *b'* are located in the same position regardless of which series is in operation, enables the operator to determine accurately the instant 40 at which the openings in the sheet will register with those in the tracker bar, for the purpose of accent, it being one of the objects of the present invention to facilitate this by keeping the operative series of openings 45 in one position relative to the motion of the sheet, no matter which scale may be in use.

As indicated in the drawings, the opposing faces of the member A and part *b* are 50 approximately equal in facial width, and that in either position of member B the sides of these parts are in superposed alinement. By this construction the member A is of sufficient width to provide a support for 55 member B throughout the entire width of said member B and thereby eliminating liability of a rocking of said member during the passage of the note-sheet, but is not of excessive greater width than said member B, 60 so that there is no requirement of the provision of an excessively large tracker box, it being understood, of course, that slight differences of width due to workmanship will not affect the fact of the parts being of approximately equal facial width. Another 65

advantage due to this feature lies in the fact that a visual positioning of the members is possible, and that there is an avoidance of any interchanging positioning devices within the area of these opposing faces, this latter 70 fact eliminating liability of damaging the parts such as would result by any attempt to disengage concealed interlocking connections should the latter become frictionally bound together. 75

While I have herein disclosed a preferable construction and arrangement of parts for attaining the desired ends, it will be understood that the same may be modified, changed or varied; I therefore desire it to 80 be understood that I reserve the right to make such necessary and desired modifications of the structure shown as may come fully within the spirit and scope of the invention as expressed in the accompanying 85 claims.

Having now described my invention, what I claim as new is:

1. A tracker bar comprising more than a single member, said members being separable and having an unequal number of ducts, one of said members being reversible end for end, and means for fixedly and rigidly securing said members together with registering ducts in either position of the reversible member. 90

2. A tracker bar comprising a permanently-positioned member, an independent member separable from and positionable relatively to said first named member, said members having an unequal number of series of ducts and being positionable to operatively connect the series of ducts of one member with one of the series of ducts of the other member, the opposing faces of said members being of approximately equal facial width, the sides of the members being in superposed alinement in any of the duct connecting positions and connecting means located on the sides of the members for connecting the members with registering ducts, the change in series connection of ducts being provided by a separation of the members and a repositioning in changed position of the members relative to each other. 105

3. A tracker bar comprising two separable members having an unequal number of ducts, said members in operative position having registering ducts and being positionable relative to each other to change the relationship in registration of the ducts of the members, the opposing faces of said members being of approximately equal facial width, the sides of the members being in superposed alinement in any of the duct connecting positions, and connecting means located on the sides of the members for connecting them together with registering ducts, said members being supported relatively to each other to prevent a change in 110 115 120 125 130

duct registration by movements other than a separation of the members, whereby a separation of the members will be required prior to a change in relative position.

5 4. A tracker bar comprising a permanently positioned member and a removable member, said members combinedly carrying ducts, the ducts of one member being greater in number than the ducts in the other member, said members being normally fixedly and rigidly secured together with registering ducts and being supported relatively to each other to prevent a change in duct registration by movements other than a separation of the members, said removable member being reversible end for end to vary the duct registration.

20 5. A tracker bar comprising a permanently positioned member and a removable member, said members combinedly carrying ducts, said permanently positioned member having a single series of duct openings, the removable member being reversible end for end and having more than a single series of 25 openings, either one of said series being adapted to register with the series of the other member when the members are connected, said members being normally fixedly and rigidly fixed together with registering 30 ducts and being supported relatively to each other to prevent a change in duct registration by movements other than a separation of the members.

35 6. The combination with a tracker bar having a series of venting ducts, of a removable tracker board having two series of ducts, each of which is registrable with the ducts of said tracker bar, said board being supported relatively to the tracker 40 bar to prevent a change in duct registration by movements other than a separation of board and bar and being reversible end for end, said board and bar being normally fixedly and rigidly secured together with 45 registering ducts.

7. The combination with a tracker bar having a series of venting ducts, of a removable tracker board having two series of ducts, each of which is registrable with 50 the ducts of said tracker bar, said board being supported relatively to the tracker bar to prevent a change in duct registration by movements other than a separation of board and bar and being reversible end for end, said board and bar being normally fixedly and rigidly secured together with registering ducts, each series of duct openings on the exposed face of the board being dissimilarly spaced.

60 8. A tracker bar comprising two separable members having an unequal number of ducts, said members being supported relatively to each other to prevent a change in duct registration by movements other than 65 a separation of the members and being po-

sitionable relative to each other to change the relationship of the ducts of the members, the opposing faces of said members being of approximately equal facial width, and means for connecting said members together in either of their positions, said means being located on the sides of the members and forming a stop against a change in relative position of the ducts of the members in a lateral direction, whereby separation of the members is required prior to a change in duct connection, said members being normally fixedly and rigidly secured together with registering ports, the sides of the members being in superposed alignment in any of the duct connecting positions.

70 9. A tracker bar comprising two separable members combinedly carrying tracker ducts, one of said members having two series of tracker openings, said members being supported relatively to each other to prevent a change in duct registration by movements other than a separation of the members, one of said members being reversible end for 75 end, and means for securing said members together with the reversible member in either of its positions, said members being normally fixedly and rigidly secured together with registering ports.

95 10. In a tracker bar for mechanical musical instruments, the combination of a stationary joining bar and a detachable bar, said detachable bar having two series of openings, said detachable bar being supported relatively to the joining bar and to prevent a change in duct registration by movements other than a separation of the detachable bar from the joining bar, said detachable bar being reversible end for end when so separated, and means for attaching said detachable bar to said joining bar, said bars being normally fixedly and rigidly secured together with registering ports.

100 11. In a tracker bar for mechanical musical instruments, the combination of a stationary joining bar having one series of ducts, and a detachable bar, said detachable bar having two series of ducts, said detachable bar being supported relatively to the 105 joining bar and to prevent a change in duct registration by movements other than a separation of the detachable bar from the joining bar, said detachable bar being reversible end for end when so separated, and means for attaching said detachable bar to said joining bar, said bars being normally fixedly and rigidly secured together with registering ports.

110 12. In a tracker-bar, a stationary joining bar having one series of ducts, and a detachable bar having two series of ducts, the opposing faces of said members being of approximately equal facial width, and means for attaching said bars together with either 115

series of detachable-bar ducts in registration of the ducts of the joining bar, said detachable bar to prevent a change in duct registration by movements other than a separation of the detachable bar from the joining bar, said means being located on the sides of the bars and forming a stop against a change in relative position of the ducts of the bars in a lateral direction, whereby separation of the bars is required prior to a change in duct connection, the sides of the bars being in superposed alinement in any of the duct connecting positions.

13. In a tracker-bar, a stationary joining bar having one series of ducts, and a detachable bar having two series of ducts, the opposing faces of said members being of approximately equal facial width, and means for attaching said bars together in either of two positions, each position registering a different series of the two series of the de-

tachable bar with the one series of the joining bar, registration of the ducts of the joining bar, said detachable bar to prevent a change in duct registration by movements other than a separation of the detachable bar from the joining bar, said means being located on the sides of the bars and forming a stop against a change in relative position of the ducts of the bars in a lateral direction, whereby separation of the bars is required prior to a change in duct connection, the sides of the bars being in superposed alinement in any of the duct connecting positions.

In testimony whereof I affix my signature in the presence of two witnesses.

WILLIAM F. COOPER.
